COSMETIC CONTAINER

Frederick R. Reutter, Waterbury, Conn., assignor
to Scovill Manufacturing Company, Water-
bury, Conn., a corporation of Connecticut

Application July 31, 1940, Serial No. 348,663

9 Claims. (Cl. 206—56)

This invention relates to improvements in containers and particularly to one for holding cosmetic materials such as lipsticks, eyebrow pencils, shaving soaps and the like, wherein a carrier cup supports the material within the container and is operated to and fro therein by a thumb piece projecting through a slot in the wall of the container.

One object of this invention is to provide a container in which the slot is so formed as to coact with the operating member or thumb piece of the carrier cup whereby said carrier cup may be held in a projected position at the open end of the container or at one or more intermediate positions within said container.

A further object is to provide a container of the above nature in which the entrance end of the longitudinal slot is provided with a means to preclude one container capping or entering within another in the bulk handling of the same during the various operations to which the container is subjected in the manufacture of the article.

The full nature of this invention along with other objects and various advantages thereof will be more apparent from a consideration of the following description when read in connection with the accompanying drawing, in which

Figure 1 is a front elevational view of a container body shell.

Figure 2 is a similar view of the fragment upper part of the shell showing the carrier cup associated therewith in a projected position.

Figure 3 is a side view of the same.

Figure 4 is a view similar to Figure 1 and showing a fragmentary portion of another shell in opposed position, illustrating how one shell is precluded from capping within each other by reason of a special shaped entrance slot.

Figure 5 shows two container shells having an old type slot and illustrates how one shell could capp within the other and

Figure 6 shows an elevational view of a modified form of the container shell wherein a series of off-set portions are provided within the path of the longitudinal slot.

Referring now to the drawing wherein like numerals designate like parts throughout the several views, numeral 10 indicates a tubular body shell such as used for the so-called push type lipstick container, having a knurled bead 11 adjacent its base end to assist as a gripping means for the container. Disposed in spaced relation and slightly above the bead 11 is a smooth bead 12 which may serve conveniently as a stop for a cover, not shown, designed to be slipped over the top of said container shell 10 to close the same. A carrier cup 13 is disposed within the container shell 10 and is adapted to slide to and fro therein by means of an operating member 14 secured thereto and

projecting through a longitudinal slot 15 provided in the body shell 10. Specifically this operating member may be a pin threaded or riveted into the side wall of the cup 13 and provided with an enlarged head 16, disposed on the outside of the shell 10 where it may be engaged conveniently by the thumb of the operator.

It is common practice in making these containers to provide an entrance to the longitudinal slot 15 of a narrower dimension than said slot and such entrance will hereinafter be referred to as a narrow throat and indicated by the numeral 17 in the several views.

The gist of this invention resides particularly in the manner in which the narrow entrance throat 17 is formed. In this case one side of the entrance throat is provided with an angular cut-out recess 18 while the opposite side of said throat is formed with a correspondingly shaped projection 19 disposed in spaced relation to said recess and providing an off-set V shaped pathway 20 at an intermediate portion of said narrow throat 17. It is to be noted here that the projection 19 is disposed crosswise of the normal straight pathway of the slot 15, the reasons and advantages of which will be explained later.

In operating a lipstick embodying the above invention, if it is desired to retain the carrier cup 13 in elevated or projected position, it is only necessary to move the carrier cup upwardly to a position where its operating pin 14 is disposed at the apex of the V shaped recess 18 in the abrupt bend of the pathway 20 in a manner as shown in Figures 2 and 3. The transverse width 35 of the V shaped pathway 20 is preferably slightly less than the diameter of the operating pin 14. The fact that the walls of the shell 10 is split clear through to the open end by reason of the narrow throat 17, the open end of the container shell 10 will spring sufficiently to allow the pin 14 to pass through said narrow throat 17 into the wider longitudinal slot 15 where it may operate with entire freedom. When the operating member 14 is disposed at the apex of the recess 18, the pointed end of the projection 19 will bear against said member 14 with sufficient force to hold it confined in said recess 18 and retain the carrier cup 13 in its elevated position while the lipstick is being applied without the necessity of the operator having to hold the thumb engaging head 16.

It is to be noted that by reason of this particular V shaped pathway 20 the projection 19 intercepts and is disposed crosswise of the normal straight pathway of the narrow throat 17a leading into a larger longitudinal slot 15a such as shown in the old form shell 10a of Figure 5.

By reason of this particular construction it will be impossible for shells when handled in bulk to capp or become interfitted one within the other during any of the manufacturing opera-

tions. During the manufacturing of the conventional type of container shell, when handled in bulk, there was always the tendency for one shell to cobb within the other in a manner as shown in Figure 5, which was a serious detriment particularly to the cleaning and finishing operations and also required an extra amount of precaution and inspection of the product when handled in bulk production to see that all the shells were in a separated state before any of the several manufacturing operations were started. By this new slot, as shown in Figure 4, the open end of any one shell is not allowed to enter in an opposed manner into another shell any further than the point where the open end of one shell would abut the outer edge of the projection 19 of the other shell in the pathway 20 as shown in Figure 4.

In Figure 6 there is shown a modified form wherein two off-set V shaped pathways 20a and 20b may be provided within the longitudinal slot 15b of the shell 10b, the slot 20a being at the entrance end of the slot 15b and the slot 20b being about half-way the length thereof. While there are only two V shaped pathways 20a and 20b shown in the longitudinal slot 15b of the modified form, it is within the purview of this invention to increase the number of off-set pathways to any desired number, thus allowing for a more graduated positioning of the carrier cup within the container shell 10b. In this modified form the operator, when starting out with a fresh lipstick, would operate the pin of the carrier cup in the lower part of the slot 15b up to and engage in the off-set pathway 20b until the stick is exhausted substantially down to the edge of the body shell 10a. The off-set pathway 20b may then be employed as a stop for the operating pin and operate the carrier cup 13 in the upper part of the container shell until the lipstick is exhausted.

While two forms of the invention are herein shown and described, it is to be understood that the construction may be varied as to mechanical details without departing from the spirit of the invention or scope of what is claimed.

I claim:

1. In a cosmetic container, the combination of a container body having a longitudinal slot and an open end, a carrier movable to and fro in said body, an operating member on the cup extending through said slot, and means disposed crosswise of said slot and forming one edge of an angular V shaped slot conjoined with said longitudinal slot, the apex of said V shaped slot adapted to receive said operating member and retain said carrier cup in a set position within said body.

2. In a cosmetic container, the combination of a container body having a longitudinal slot extending substantially the length of the body and opening from the body through a narrow throat, a carrier cup movable to and fro in said body, an operating member on the cup extending through said slot, and an angular off-set pathway arranged transversely of and forming a part of said narrow throat and adapted to receive said operating member and retain said carrier cup in a set position within said body.

3. In a cosmetic container, the combination of a container body having an open end and a longitudinal slot extending substantially the length of the body through the open end thereof, a carrier cup movable to and fro in said body, an operating member on the cup extending through

said slot, and means disposed crosswise of said slot adjacent its open end and forming one edge of an angular V shaped slot conjoined with said longitudinal slot, the apex of said V shaped slot adapted to receive said operating member and retain said carrier cup in a set position within said body.

4. In a cosmetic container, the combination of a container body having an open end and a longitudinal slot extending substantially the length of the body through the open end thereof, a carrier cup movable to and fro in said body, an operating member on the cup extending through said slot, and a series of spaced off-set V shaped relatively narrower slots disposed in the pathway and transversely of said longitudinal slot and cooperating with said operating member to retain said carrier cup in any one of several positions.

5. As an article of manufacture, a body shell for a container having an open end and a longitudinal slot extending through the open end thereof, and means disposed adjacent the open end and extending from one edge of said slot and traversing substantially the entire normal width of said slot to preclude the cobbing or entrance of like articles within each other in the bulk handling of the same.

6. As an article of manufacture, a body shell for a container having an open end and a longitudinal slot extending through the open end thereof, lug means projecting from one edge of said slot adjacent the open end thereof and forming one edge of a V shaped pathway offset from the normal straight pathway of said slot and serving to preclude the cobbing or entrance of like articles within each other in the bulk handling of the same.

7. As an article of manufacture, a body shell for a container having a longitudinal slot and opening from the shell through a narrow throat, and means disposed crosswise of said throat and forming one edge of an angular V shaped slot conjoined with said longitudinal slot and designed to preclude the cobbing or entrance of like articles within each other in the bulk handling of the same.

8. As an article of manufacture, a body shell for a container having an open end and a longitudinal slot extending through the open end thereof, a lug projecting substantially across the width of the open end of said longitudinal slot from one edge thereof, and the opposite edge of said slot having a complementary recess spaced from and diametrically opposite of said lug.

9. In a cosmetic container, the combination of a container body having a longitudinal slot extending substantially the length of the body and opening from the body through a relatively narrower throat, a carrier cup movable to and fro in said body, an operating member secured to said cup, extending through said slot and comprising an enlarged head and a reduced neck portion, and an angular off-set pathway arranged transversely and at intermediate part of said narrower throat, the width of said narrower throat and off-set pathway being slightly less than the cross dimension of said operating member neck portion whereby necessitating the springing the upper portion of the container body and causing the operating member to be snapped into registry with the apex of said angular pathway as a positive stop for the carrier cup.

FREDERICK R. REUTTER.
